DESCRIPTION

U.S. PATENT DOCUMENTS

FIG. 1 is a perspective view of my new design for a pair of
motorcycle foot heel rest restraints, showing the left one of
the pair, with the heel rest shown in broken lines for
illustrative purposes only and forming no part of the design.
FIG. 2 is an enlarged rear view of my new design.
FIG. 3 is a front view of FIG. 2.

FIG. 4 is a right side view of FIG. 2.

FIG. 5 is a left side view of FIG. 2.

FIG. 6 is a top view of FIG. 2; and,

FIG. 7 is a bottom view of FIG. 2.

The right of the pair of motorcycle foot heel rest restraints
is a mirror image of the left of the pair, as shown in FIGS.
1-7.
